UNITED STATES PATENT OFFICE.

KARL VIKTOR RUDIN, OF STOCKHOLM, SWEDEN.

ZERO-RESETTING DEVICE.

Application filed August 2, 1918. Serial No. 247,968.

To all whom it may concern:

Be it known that I, KARL VIKTOR RUDIN, correspondent, subject of the King of Sweden, residing at 12 Karduansmakaregatan, Stockholm, Sweden, have invented certain new and useful Improvements in Zero-Resetting Devices, of which the following is a specification.

This invention relates to improvements 10 in calculating machines and more particularly to that class of calculating machines in which the values of the calculations are set on setting disks, having a variable number of teeth adapted to transmit the said 15 values to a registering mechanism which is mounted on a slideable carriage adapted to be shifted laterally along the setting mechanism, so that its registering elements or numeral wheels can be brought into cooperation 20 with any of the setting disks of the setting mechanism. Between said setting and registering mechanisms are arranged locking members intended to be actuated by shoulders, mounted upon the setting mechanism 25 and at predetermined times to lock the registering mechanism. Said locking members are arranged in such a way that they only by their own weight aim to mesh with a registering mechanism and cause the numeral 30 wheels to rotate with a step-by-step movement.

Such a calculating machine has been described in my U. S. A. patent application Serial No. 224,822, filed March 26, 1918. For 35 returning the registering elements or the numeral wheels of the registering mechanism to zero position known mechanisms are used. In resetting the numeral wheels to zero position said locking members must 40 be thrown out of engagement with the numeral wheels. Several arrangements have been proposed for that purpose. One of said arrangements consists therein that the locking members are actuated by springs 45 causing to hold the numeral wheels in correct position. In resetting the numeral wheels to zero position said locking members are rocked together with their springs in a radial direction away from the numeral 50 wheels. This construction is objectionable in so far as it requires much room, so that certain locking members or detent mechanisms cannot be used. Apart from this when rocking the spring actuated detent elements radially the throw of the said elements

which corresponds to the height of the teeth is comparatively large.

Another arrangement has been proposed in order to avoid said drawbacks. In accordance with said last arrangement the locking members or the detent mechanism are mounted in such a way that for throwing it out of engagement with the numeral wheels it is shifted in a direction parallel to the axis of the numeral wheels. 65

Both of said arrangements are, however, objectionable in so far as they are only actuated by springs, whereby their operation necessitates a large amount of manual labor. A quick wearing out of the parts is also 70 caused. Further the mechanisms for the operation of said zeroising arrangements requires much room and more particularly the latter arrangement requires a second slide which complicates the arrangement. 75

The object of the present invention is to provide a zero setting or adjusting mechanism in which these objections are avoided.

For the purpose of explaining the invention an example embodying the same has 80 been shown in the accompanying drawing in which the same letters of reference have been used in all the views to indicate the corresponding parts.

In said drawing—Figure 1 is a vertical 85 cross-section of the machine illustrating setting and registering mechanisms of a calculating machine of that class, having setting disks with a variable number of teeth. Fig. 2 is an end side-view of the 90 carriage seen from the right end with the cover plates and the usual wing-nut for the zeroising operation removed. Fig. 3 is a side view of a casing enclosing the zeroising means connected with the wing nut, viz 95 100 105

Referring to Fig. 1, rotary shaft 1 is mounted in a pair of side walls 2 of the casing of the machine (only one of said side-walls is illustrated). The said shaft is operatively connected with the machine crank 3 through spur gears 4 and 5, and it carries a plurality of setting disks 6 each of which is provided with nine radial slots. Within the latter, radially shiftable teeth 7 are located which with lateral noses engage in a 110

cam slot formed in a cam disk 8 loosely mounted on the shaft 1. By rotating the said disk on the shaft 1 by means of a handle 9 any desired number of the teeth 7 can be shifted into a position beyond the periphery of the setting disk. The number of the teeth shifted beyond the periphery of the setting disks represents the value to be introduced in the calculation in each column of the registering mechanism. In front of said setting disks, the whole of which may be termed the setting mechanism, numeral wheels 10 are loosely mounted on a shaft 11 disposed parallel to the shaft 1. Each of the said numeral wheels is provided at its circumference with the numerical characters from "1" to "9" and the "0" sign, and one of the said characters of each column of numeral wheels is at a time displayed through a peep hole 12, made in a cover 13, which is common to all the numeral wheels. Each of the numeral wheels has a spur gear 14, secured to its side which is provided with ten teeth, and the latter are in mesh with the teeth of a transmission wheel 15 which is loosely mounted on a shaft 16 disposed parallel to the shaft 11 of the numeral wheels. The said transmission or intermediate gears 15 which are mounted on the same axis 16 are located in the plane of the radially shiftable teeth 7 of the setting disks 6, and when rotating the said disks 6 by means of the machine crank 3 the teeth 7 mesh with the teeth of the transmission wheel 15 so as to advance the same. Thereby also the numeral wheels are advanced a distance which corresponds to the number of teeth 7 projected into their operative positions beyond the periphery of the setting disks 6. In order to transmit a certain number to the numeral wheels 10 the operator sets the said number on the setting disks 6, whereupon he rotates the crank.

Carrying means are provided between consecutive numeral wheels which shift a numeral wheel forward or backward the distance corresponding to one value, if the numeral wheel of the next lower order passes from its "9" position into its "0" position, or vice versa. Rocking levers 17 having the form of hammers are used for this purpose, which levers are loosely mounted upon a shaft 18 disposed parallel to the axis of the registering mechanism and which extends with their free upper ends to points adjacent to the gear wheels 15. Each of the numeral wheels is provided with a pin 19 which strikes the head 20 of the hammer 17 so as to rock the latter, when the numeral wheel passes from its "9" position into its "0" position, and vice versa. Thereby a cam surface 21 of the rocking lever 17 is thrown into the path of a laterally shiftable tooth 22 of the cooperating setting disk 6. Upon rotation of the setting disk 6 the cam face 21 shifts the tooth 22 laterally and into

mesh with the teeth of the transmission or intermediate gear wheel 15 cooperating with the numeral wheel of the next higher order. Thereby the said numeral wheel 10 is advanced the distance of one value. As, for the purpose of performing additions or subtractions, or multiplications or divisions, the crank can be turned either to the right or to the left, two teeth 22 and cam faces 21 are provided, only one of which is operative when turning the crank in one direction. At the end of the carrying operation cam faces on the setting disks rock the levers 17 into their normal positions shown in Fig. 1.

The numeral wheels are locked by means of detents or rocking levers which prevent the said wheel from overthrowing. Said detents or rocking levers 23 are in a way described in my patent application No. 224,322, filed on the 26th of March 1918, arranged in such a way that they by their own weight aim to mesh with the registering elements or the numeral wheels. Said detents or rocking levers 23 are actuated by shoulders 35 and 36 on the setting disks and the cam disk respectively.

For returning the wheels 10 to the zero-position a wing-nut 24 is arranged at the right end of the slide or carriage 25 containing the registering mechanism. Said wing-nut is rigidly connected with an interior cog-rim 26 (Fig. 3) adapted to engage with a cog-wheel 27, mounted upon the shaft 11 for the numeral wheels 10. The cog-rim 26 is rotatably mounted with a casing 28.

The now described parts of the machine are before known and form no part of the present invention.

As before mentioned the locking members or pawls 23 must be released from the numeral wheels in order to enable the numeral wheels to be reset into their zero position. In order to make this possible in a simple and reliable way there is arranged a shaft 29 extending through the carriage 25. Said shaft 110 is only rotatably or may also be rigidly attached to the carriage. Said latter embodiment is preferred and is illustrated on the drawing. Upon the shaft is loosely mounted a bar 30, common for all the pawls or locking members 23, provided with an arm or projection 31, intended to lie against the outer periphery of the cog-rim 26. Said cog-rim is for that purpose provided with one or two slots 32, in the one of which 115 the arm or projection 31 rests normally. In order to make it possible for said arm or projection to swing out so as to slide against the outer periphery of the cog-rim 26 the casing 28 is provided with a projecting part 120 33. The casing is further provided with ears 34 for fastening it together with the carriage or slide.

On resetting the numeral wheels back to zero position the wing-nut 24 is acted on in 130

the usual manner. Thereby the numeral wheels are in known way by means of the cog-rim 26 and the cog-wheel 27 returned to zero position. At the same time the arm 5 or shoulder 31 is caused to swing out from the slot or recess 32 and to slide against the outer periphery of the said cog-rim. Thereby the bar 30 is turned about its shaft 29 and in the direction against the locking member 10 or pawls 23 so as to release the same from the numeral wheels. Said wheels can therefore in known way be rotated for the purpose of being reset into the zero position. After the zero setting operation has been 15 carried out—in the case now in question after half a revolution of the nut 24—the arm or projection 31 engages in the other slot or recess 32 in which operation the numeral wheels are once more locked by the 20 locking members or pawls 23.

It must be remarked that by the said combination of the arm or projection 31 and the slots or recesses 32 the wing nut 24 is locked each time after having carried out a zero- 25 setting operation.

I claim:

1. In a calculating machine, the combination with a setting mechanism, a registering mechanism, locking members intended 30 to be actuated by shoulders mounted upon the setting mechanism and at predetermined times to lock the registering mechanism, means for returning the registering elements to zero, of a bar mounted upon a shaft parallel to that of the locking members arranged 35 for actuation by the said zeroising means, in order to turn in the direction against the locking members and to release the same from the numeral wheels.
2. In a calculating machine, the combination with a setting mechanism, registering elements, a locking member intended to be 40 actuated by shoulders mounted upon the

setting mechanism, means for returning the registering elements to zero, of a bar mounted 45 upon a shaft parallel to that of the locking member provided with an arm or projection intended to be actuated against the locking member and to release the same from the numeral wheels.

3. In a calculating machine, the combination of a setting mechanism, a registering mechanism, locking members intended to be actuated by shoulders mounted upon the setting mechanism and at predetermined 50 times to lock the registering mechanism, means to return the numeral wheels to zero and including an interior cog-rim having a recess in its outer periphery, a bar having an arm or projection normally engaged in said 55 recess and which during the rotation of the cog-rim slides against the outer periphery thereof and moves said bar against the locking members to release the latter from the numeral wheels.

4. In a calculating machine, the combination with a setting mechanism, a registering mechanism, locking members intended to be actuated by shoulders mounted upon the setting mechanism and at predetermined 70 times to lock the registering mechanism, means for returning the numeral wheels to zero, and including a wing nut and an interior cog-rim having recesses in its outer periphery and a bar mounted upon a shaft 75 parallel to that of the locking members having an arm or projection normally engaged in one of said recesses and securing the wing nut in locked, zero-setting position.

In testimony whereof I affix my signature 80 in presence of two witnesses.

KARL VIKTOR RUDIN.
